US0D1095632S

(12) **United States Design Patent** (10) **Patent No.:** **US D1,095,632 S**
(45) **Date of Patent:** **** Sep. 30, 2025**

(54) **ROBOT**

(71) Applicant: **Clutterbot, Inc.**, Claymont, DE (US)

(72) Inventors: **Justin David Hamilton**, Wellington (NZ); **Sergio Zapata Velásquez**, Medellín (CO); **Kimberley Atwell**, Wellington (NZ)

(73) Assignee: **Clutterbot, Inc.**, Claymont, DE (US)

(**) Term: **15 Years**

(21) Appl. No.: **29/957,836**

(22) Filed: **Aug. 15, 2024**

(51) **LOC (15) Cl.** **15-99**

(52) **U.S. Cl.**

USPC **D15/199**

(58) **Field of Classification Search**

(57) **CLAIM**

The ornamental design for a robot, as shown and described.

DESCRIPTION

FIG. 1 is a top, front, right perspective view of a robot showing the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a front elevation view of the robot in FIG. 1, in a first alternate position;

FIG. 9 is a right-side elevation view thereof;

FIG. 10 is a top, front, right perspective thereof;

FIG. 11 is top, front, right perspective view of the robot in FIG. 1, in a second alternate position;

FIG. 12 is a front elevation view thereof;

FIG. 13 is a right-side elevation view thereof;

FIG. 14 is front elevation view of the robot in FIG. 1, in a third alternate position; and,

FIG. 15 is a right-side elevation view of the robot in FIG. 1, in a fourth alternate position.

The broken lines show portions of the robot which form no part of the claimed design.
